(57) CLAIM

We claim the ornamental design for a candle, as shown and described.

DESCRIPTION

FIG. 1 is a top perspective view of a candle according to the present invention;

FIG. 2 is a front view of the candle of FIG. 1;

FIG. 3 is a rear view of the candle of FIG. 1;

FIG. 4 is a right-side view of the candle of FIG. 1;

FIG. 5 is a left side view of the candle of FIG. 1;

FIG. 6 is a top view of the candle of FIG. 1; and,

FIG. 7 is a bottom view of the candle of FIG. 1.

The portion of the candle shown in broken lines forms no part of the claimed design.
